[57] CLAIM

The ornamental design for a pegboard hook guard, as shown.

DESCRIPTION

FIG. 1 is a top plan view of a pegboard hook guard incorporating our new design.

FIG. 2 is a side elevational view of the guard.

FIG. 3 is a bottom plan view of the guard.

FIG. 4 is a front elevational view of the guard.

FIG. 5 is a rear elevational view of the guard.

FIG. 6 is an enlarged cross-sectional view taken along the line 6—6 of FIG. 1.

FIG. 7 is an enlarged cross-sectional view taken along the line 7—7 of FIG. 1.
